Primary Examiner — Katrina A Betton(74) *Attorney, Agent, or Firm* — Lerner, David, Littenberg, Krumholz & Mentlik, LLP**(57) CLAIM**

The ornamental design for an autonomous vehicle door, as shown and described.

DESCRIPTION

FIG. 1 is a front perspective view of an autonomous vehicle door according to our design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top elevation view thereof; and,

FIG. 7 is a bottom elevation view thereof.

Broken lines are environmental only and form no part of the claimed design.
